(57) **CLAIM**

The ornamental design for a sample holder for a device for measuring fluorescence polarization, as shown and described.

DESCRIPTION

FIG. 1 is a top and left front perspective view of a sample holder for a device for measuring fluorescence polarization, showing our design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a top, front and left side elevational view thereof showing the sample holder in an open position when mounted on a housing device for measuring fluorescence polarization.

The broken line showing in the drawings is for illustrative purposes only and forms no part of the claimed design.
